CLAIM

The ornamental design for a frame for a child's automobile seat, as shown and described.

DESCRIPTION

FIG. 1 is a front and top perspective view of a frame for a child's automobile seat, showing our new design;
FIG. 2 is a rear and top perspective view thereof;
FIG. 3 is a view similar to FIG. 1, but with the backrest folded back; and
FIG. 4 is a view similar to FIG. 2, but with the backrest folded under.

FIG. 1

FIG. 2

FIG. 4

FIG. 3
